UNITED STATES PATENT OFFICE.

JOHN H. FITCH, OF LUDINGTON, MICHIGAN.

STREET-CAR SWITCH MECHANISM.

SPECIFICATION forming part of Letters Patent No. 777,889, dated December 20, 1904.

Application filed September 14, 1904. Serial No. 224,405.

To all whom it may concern:

Be it known that I, JOHN H. FITCH, a citizen of the United States, residing at Ludington, county of Mason, State of Michigan, have 5 invented a certain new and useful Improvement in Street-Car Switch Mechanism, of which the following is a specification, reference being had to the accompanying drawings, which form a part of this specification.

10 My invention has for its object certain new and useful improvements in a street-car switch of superior simplicity, economy, and utility; and it consists of the construction, combination, and arrangement of devices hereinafter 15 described and claimed, and illustrated in the accompanying drawings, in which—

Figure 1 is a view in side elevation illustrating features of my invention. Fig. 2 is a plan view of certain features of the construction. 20 Fig. 3 is a view in section on the line 3 3, Fig. 2. Fig. 4 is a view in section on the line 4 4, Fig. 3. Fig. 5 is a plan view with parts of the car omitted.

In the drawings, *a* represents a portion of a 25 car-frame, and *b* a portion of the truck-frame.

c c denotes the rails, and *d* the switch-point of any ordinary or desired construction.

My invention has reference more particularly to, first, the mechanism connected with 30 the switch-point for operating the same; second, the mechanism attached to the car for actuating the mechanism connected with the switch.

To actuate the switch-point, I employ a rocking lever *e*, arranged between the rails of the track, with which is connected a rocking shaft *f*, provided at one extremity with the crank-arm *g*, united to a connecting-rod *h*, connected with the switch-point *d*. The rocking lever *e* and the shaft *f* are preferably located in 35 a suitable case *i*, the lever *e* projecting through one end of the case and fulcrumed therein, as at *j*, so that one end of the lever will project above the surface of the case and sufficiently 40 above the bed of the track to be engaged by a suitable implement attached to the car to tilt said lever, the opposite extremities of the lever *e* rising alternately as said lever is tilted. Attached to the lever *e* preferably is a locking-arm *k* to engage a notched spring *l* to lock 45

the lever *e* in a given position. The spring *l* is preferably bolted at one end to the switch-case, as indicated at *m*. The case is preferably constructed with flanges, (indicated at *n*,) through which it may be secured upon the ties. 55 Attached to the truck-frame I have shown hangers *p*, carrying a shaft *q*, upon which is fulcrumed tripping levers or shoes, (indicated at *r*.) Attached to the car-frame are bell-crank levers *s*, the same being fulcrumed, as at *t*. The 60 bell-crank levers are connected, as by rods *u*, with the shoes *r*. With the opposite ends of the bell-crank levers are connected foot-levers *v*, in position for the motorman or driver of the car to readily engage the same to throw the bottom of the corresponding shoe *r* down into working position, so as to ride over the corresponding end of the rocking lever *e* and tilt said lever. Springs *w* are employed to normally elevate the bottom of the shoes *r* to lifted 65 position. (Shown in dotted lines in Fig. 1.) It will readily be seen that as the lever *e* is tilted the shaft *f* is correspondingly tilted to rock its crank-arm *g* and shift the switch-point. 70

What I claim as my invention is—

1. In a street-car switch the combination with a switch-point of a rock-shaft extending longitudinally of the track provided with a crank-arm at one end thereof connected with the switch-point, a tilting lever connected with the opposite end of said rock-shaft arranged to tilt in a direction transversely of the track, means to lock the tilting lever in a given position, and mechanism carried by a moving 80 car to trip the tilting lever.

2. In a street-car switch the combination with a switch-point of a rock-shaft provided with a crank-arm at one end thereof, a rod connecting the point with the crank-arm, a 85 tilting lever connected with the opposite end of the shaft arranged to tilt in a direction transversely to that of the shaft, a case for the tilting lever and rock-shaft, means within the case to lock the tilting lever in a given 90 position, and means carried by a moving car to actuate the tilting lever.

3. In a street-car switch mechanism a case, a tilting lever fulcrumed within the case to tilt 95 in a direction transversely of the track, a rock-

shaft provided with a crank-arm at one end thereof connected at one end with the tilting lever intermediate the extremities of the lever, a crank-arm at the opposite end of said 5 shaft connected with the switch-point, means within the case to lock the tilting lever in a given position, and means carried by the moving car to engage one extremity of the tilting lever to actuate said lever.

10 4. In a street-car switch mechanism the combination of a case, a tilting lever, a connecting rock-shaft having a locking movement within said case, means to connect the switch-point with one extremity of the 15 rock-shaft, a notch-spring within the case and an arm connected with the tilting lever to engage said spring and hold the tilting lever in a given position.

5. In a street-car switch mechanism the 20 combination of a case, a tilting lever arranged within the case to tilt in a direction transversely of the track, and having its extremities arranged to alternately rise above the case, a shaft connected with the tilting lever 25 extending longitudinally of the track, a spring

with a crank-arm connected with a switch-lever, and means carried by a moving car to trip the tilting lever.

6. In a street-car switch the combination with a switch-point of a rock-shaft provided 30 with a crank-arm connected with a switch-point, a tilting lever connected with the rock-shaft arranged to tilt in a direction transversely of the track, means to rock the tilting lever in a given position, and mechanism carried by a moving car to trip the tilting lever, 35 said mechanism comprising tripping-levers fulcrumed intermediate their ends upon the car, bell-cranks connected with the upper ends of the tripping-levers, and foot-levers connected with the opposite ends of the bell-cranks, respectively.

In testimony whereof I have signed this specification in the presence of two subscribing witnesses.

JOHN H. FITCH.
